UNITED STATES PATENT OFFICE.

PAUL LOCHMANN, OF ZEITZ, PRUSSIA, GERMANY.

STEAM-ENGINE.

SPECIFICATION forming part of Letters Patent No. 244,135, dated July 12, 1881.

Application filed March 14, 1881. (No model.)

To all whom it may concern:

Be it known that I, PAUL LOCHMANN, residing at the city of Zeitz, in the Kingdom of Prussia, in the German Empire, have invented 5 Improvements in SteamEngines, of which the following is a specification.

This invention has reference to an improved construction of steam-engines in which the generation of the steam and the utilization of 10 the same for motive purposes take place in the same space by expansion and condensation, so that the employment of a separate steam-boiler is dispensed with and the same quantity of water, with but small additions, continually used for the generation of the steam.

The invention consists of a steam-cylinder which is open at the top and provided at the bottom with a cylindrical extension of equal diameter therewith. This extension is closed 20 at the bottom, and forms the boiler of the engine, it being surrounded by the furnace. The steam-cylinder is surrounded by a jacket, which is divided by a horizontal partition into two compartments, the upper one of which is supplied 25 with cooling-water, while the lower one is filled with a non-conductor of heat. A tightly-fitting main piston works in the upper part of the cylinder and transfers its motion by connecting-rods to the crank-shaft of the 30 engine, while a second hollow cylindrical piston, below the main piston, but of less diameter than the steam-cylinder, serves to steer or govern the motion of the main piston, its piston-rod being guided by a packing in the cylindrical center portion of the main piston, and 35 connected by a set of compound levers to the crank-shaft of the engine outside of the fly-wheel, said crank being placed at a proper angle to the crank of the connecting-rods.

40 In the accompanying drawings, Figure 1 represents a vertical central section of my improved steam-engine; and Figs. 2, 3, 4, and 5 are vertical central sections of the steam-cylinder and main and steering pistons, showing the relative positions of the same for each 45 quarter of a revolution of the driving crank-shaft.

Similar letters of reference indicate corresponding parts.

50 Referring to the drawings, *a* represents a vertical steam-cylinder, which is surrounded by a jacket, *a'*, that is divided by a horizon-

tal partition into an upper cooling-chamber, *c*, and a lower chamber, *d*. The upper chamber, *c*, is continually supplied with cold water, 55 while the lower chamber, *d*, is filled with a suitable non-conductor of heat, such as ashes and the like. The lower chamber, *d*, serves for separating the cooling-chamber *c* from the furnace *b*, which is arranged below the cylinder *a*, and securely and tightly connected to the bottom flange of the same. To the bottom of the main cylinder is furthermore tightly secured a cylindrical extension, *e*, of steel or boiler-iron, which is equal in diameter with 60 the main cylinder and closed at the bottom. The cylindrical extension *e* is surrounded by the furnace, its bottom being at a suitable distance above the grate of the same, as shown clearly in Fig. 1. The extension *e* of the steam-cylinder forms the boiler of my improved 70 steam-engine.

The main cylinder *a* is open at the top, and guides in the upper part a tightly-fitting main piston, *k*, to the central cylindrical portion, *k'*, 75 of which are pivoted the lower ends of two connecting-rods, *l*, the upper ends of which are pivoted to the crank *m'* of the crank-shaft *m*. A second hollow cylindrical piston, *g*, is arranged below the main piston *k*, and made 80 somewhat smaller in diameter than the main cylinder *a* and its boiler-extension *e*. The lower piston, *g*, is closed at the top and bottom, and is of such length as to be always, whatever its position, partly in the steam-cylinder *a* and partly 85 in the boiler-extension *e*. The lower piston, *g*, serves as a steering or governing piston for the main piston *k*, for which purpose its piston-rod *g'* is conducted through the cylindrical center portion, *k'*, of the piston *k* and tightly 90 fitted thereto by packing. The lower steering-piston, *g*, receives vertically-reciprocating motion from a crank, *n*, which is keyed to the outer end of the crank-shaft *m* by means of two pairs of levers, *i i'*, of which the outer levers, *i i'*, are 95 pivoted respectively to the crank *n* and to the head of the piston-rod *g'*, while the intermediate levers, *i' i'*, are keyed respectively to the outer end and to the center of a transverse shaft, *i''*, which turns in bearings of bracket-shaped arms of the crank-shaft supporting standards at the top of the main cylinder, as 100 shown in Fig. 1.

The cylinder *a* is provided with a valved

supply-opening, *h*, through which the boiler-extension *e* is filled with water up to a level with the testing-cock *h'*, which is connected by a pipe, *h*², with the lower part of the boiler-extension *e*. The water, once filled in, is used continually, but requires replenishing from time to time, owing to the loss caused by steam escaping at the piston, and by superheating.

The engine works as follows: By starting the fire in the furnace the water in the extension *e* is partly changed to steam. The steam passes around the steering-piston in upward direction and acts upon the main piston, carrying the same in upward direction, as shown in Fig. 2. This upward motion is kept up by the action of the steam upon the piston *k* one-quarter of a revolution of the crank until the piston assumes the position at the upper end of the cylinder shown in Fig. 2. At the same time the steering-piston arrives at its highest position and commences its downward motion in obedience to the motion of its crank, so that it assumes the position shown in Fig. 3, while the main piston passes over the dead-point. In the meantime, the influence exerted by the cooling-water in the chamber *c* upon the steam between the main and steering pistons condenses the same and creates a partial vacuum in the space between the pistons, so that the atmospheric pressure exerted upon the top of the main piston forces the same downward, which motion is continued, as the condensation proceeds, until the piston assumes the position shown in Fig. 4. In this position the steering-piston begins to follow again the main piston while the latter is passing over the second dead-point, so that the vacuum is gradually diminished and steam-pressure exerted again upon the main piston, as in Fig. 1. The play of the pistons continues in this manner, so as to impart thereby rotating motion to the crank-shaft *m*.

The regular motion of the engine is controlled by a governor, which is connected with a valve, which opens from the main cylinder to the outside. It requires but a few minutes to get up steam and start the engine, as the small quantity of water in the boiler-extension is quickly heated.

The engine consumes considerably less fuel than the furnaces of even small steam-boilers and caloric engines, while but a small quantity of cooling-water per horse-power is re-

quired for condensation, of which that only requires to be renewed from time to time which evaporates in the open air.

In this manner a compact, cheap, and effective steam-motor for small machinery is obtained, which, by its economical working, can effectually compete with the air, gas, and other motors constructed for these purposes.

Having thus described my invention, I claim as new and desire to secure by Letters Patent—

1. In a steam-engine, the combination, with a main cylinder, *a*, surrounded at one end by a cooling-chamber and at the other end by an insulating-chamber, of a cylindrical boiler-extension, *e*, in line with the main cylinder and with a furnace surrounding the boiler-extension, all arranged substantially as described.

2. The combination of the main cylinder *a*, having a steam-generating extension, *e*, with a tightly-fitting main piston, *k*, and steering or governing piston below the same, and with means, substantially as described, whereby the relative positions of the pistons toward each other are changed, and thereby rotary motion transmitted to the driving crank-shaft, substantially as set forth.

3. In a steam-engine, the combination of a main cylinder, having a cylindrical steam-generating extension, *e*, with the main piston *k*, having a central cylindrical portion, and with a steering or governing piston, the piston-rod of which is tightly fitted to the cylindrical center portion of the main piston, substantially as and for the purpose specified.

4. In a steam-engine, the combination of the main cylinder *a*, having a steam-generating extension, *e*, with a reciprocating main piston, *k*, having a central cylindrical portion, *k'*, with a steering or governing piston, *g*, below the main piston, the piston-rod of the steering-piston being guided and tightly fitted to the central portion of the main piston, and with connecting-rods *l*, double sets of pivoted and fulcrumed levers *i* *i'*, and crank *m'* and *n* of the main driving crank-shaft *m*, substantially as and for the purpose specified.

In testimony whereof I have signed my name to this specification in the presence of two subscribing witnesses.

PAUL LOCHMANN.
